UNITED STATES PATENT OFFICE.

ISING RHEINBERG AND JULIUS RHEINBERG, OF LONDON, ENGLAND.

COMB.

SPECIFICATION forming part of Letters Patent No. 662,305, dated November 20, 1900.

Application filed December 5, 1899. Serial No. 739,278. (No model.)

To all whom it may concern:

Be it known that we, ISING RHEINBERG and JULIUS RHEINBERG, manufacturers, subjects of the Queen of Great Britain, residing at 5 London, England, have invented certain new and useful Improvements in Hair-Combs, of which the following is a specification, reference being had to the accompanying drawings, in which—

10 Figure 1 is a plan of a partly-manufactured comb. Fig. 2 is a transverse section of the same. Fig. 3 is a similar section after the wires forming the teeth have been bent, as hereinafter described, and Fig. 4 is a section 15 of the same after the backing-strip has been applied thereto. Fig. 5 is a transverse section, on an enlarged scale, of a comb constructed according to our invention, wherein the teeth are secured in the longitudinal 20 strips by pressure. Fig. 6 is a similar section after the backing-strip is applied. Fig. 7 is a longitudinal section of a portion of the comb, taken on the line $z z$, Fig. 5. Fig. 8 is a side view of a portion of the comb, the backing-strip being partially removed. Figs. 9 25 to 12 illustrate modifications hereinafter described.

Like letters of reference denote corresponding parts in the several figures.

30 The strips of wire A A, Fig. 1, which are to form the teeth of the comb, are laid parallel to each other and the required distance apart, (which operation may be facilitated by the use of a suitably-grooved block,) and 35 then longitudinal strips of metal B B, which may be of U section, are placed over the ends of the wires and the wires are secured in said longitudinal strips by pressure or by pressure and bending, which will hold them firmly and 40 prevent them from drawing out and from being displaced laterally. Having thus formed a ladder-like article, as shown in Fig. 1, we next bend the same along its median line xx to form the teeth and to bring the two longitudinal 45 strips B B together, or nearly so, as indicated in Fig. 3. The comb thus formed may be used in that condition; but we prefer to strengthen it by applying thereto a suitable backing-strip C, as indicated in Fig. 50 4, covering both the aforesaid strips B and affording great rigidity. Each tooth of the comb formed in this manner is thus consti-

tuted by a strip of wire bent in the middle, the point of the tooth being formed by the bend. The two sides of the bent wire are opposite each other, and great lateral strength is thereby insured. This method of construction allows of the use of plated wires and plated backing-strips in the manufacture, so that the comb when built up does not require 55 to be subjected to any plating or finishing operation, and a further advantage of this construction is that hard wires may be used, since the same are only subjected to one bending operation.

In securing the wire teeth in the longitudinal strips by pressure we use dies which are preferably shaped and adapted to form transverse depressions b, Fig. 7, in the longitudinal strips B between the wires and a 60 longitudinal hollow or bend in the strips B at b , the wires being similarly bent at the same time, the said dies being also adapted to curve the strips B, as indicated in Figs. 5 and 6. When the strips B have been firmly 65 pressed on the wires and shaped as above indicated, it will be found that the teeth are securely held and cannot draw out or move laterally. The wires A are next bent along 70 their median line, as above described, and 75 the strips B are covered and strengthened by an additional backing-strip C placed over them. Said backing-strip is held in position 80 by the spring of the wire teeth. The arch formation of the strips B insures great rigidity. 85

We have found by experiment that the form shown in Figs. 5 to 8 is best adapted for the purposes of our invention; but we may vary the shapes given to the strips B. For example, we may use dies that will produce the 90 bends shown in Figs. 9 and 10 or that will produce flats or depressions on both sides of the wires, as shown in Fig. 11, or on one side, as shown in Fig. 12, besides the transverse depressions in the strips B between the 95 wires. In some instances grooves or notches may be formed in the wires, and the strips B may then be forced into the said notches.

The above-described method of fixing the wire teeth in the backing-strips can also be 100 used in the manufacture of metal combs having teeth of single wires free at their outer ends and fixed at their inner ends in the strips B, which are pressed tightly upon them.

In another application filed on even date herewith we have claimed the process or method of manufacture of our improved combs, and we therefore limit the claims in 5 this application to the product.

We claim—

1. In a metal hair-comb, the combination of a number of wires arranged parallel to each other, each wire returned upon itself at its 10 median line, and longitudinal metal strips inclosing and secured upon the ends of said wires, substantially as described.
2. In a metal hair-comb, the combination of a number of wires arranged parallel to each 15 other, each wire returned upon itself at its median line, and longitudinal metal strips inclosing and secured upon the indented ends of said wires, said metal strips being bent along a longitudinal line, substantially as de- 20 scribed.
3. In a metal hair-comb, the combination of a number of wires arranged parallel to each other, each wire returned upon itself at its 25 median line, and longitudinal metal strips inclosing and secured upon the indented ends of said wires, said metal strips being bent along a longitudinal line, and also having de- 30 pressions between each pair of adjacent wires, substantially as described.
4. In a metal hair-comb, the combination of a number of wires arranged parallel to each other, each wire returned upon itself at its me- 35 dian line, longitudinally-folded metal strips inclosing and secured upon the ends of said wires, and a backing-strip inclosing said longitudinal strips, substantially as described.

5. In a metal hair-comb, the combination of a number of wires arranged parallel to each other, each wire returned upon itself at its median line, and longitudinal metal strips inclosing and secured upon the indented ends 40 of said wires, said metal strips being bent along a longitudinal line, and also having de- 45 pressions between each pair of adjacent wires, and a backing-strip inclosing said longitudinal strips, substantially as described.

6. A metal hair-comb, comprising a number of wires arranged parallel to each other thus forming comb-teeth, and a metal strip folded longitudinally and inclosing the ends of the 50 wires, said folded strip being bent longitudinally, and the wires being deformed near their ends and lying within the bent portions of the strip, substantially as described.

7. A metal hair-comb, comprising a number 55 of wires arranged parallel to each other thus forming comb-teeth, and a metal strip folded longitudinally and inclosing the ends of the wires, said folded strip being bent longitudinally, the wires being deformed near their 60 ends and lying within the bent portion of the strip, and the strip being provided with indentations between the wires, substantially as described.

In witness whereof we have hereunto set 65 our hands in presence of two witnesses.

ISING RHEINBERG.
JULIUS RHEINBERG.
